(57) **CLAIM**

We claim the ornamental design for a clamping pliers with a pistol handle, as shown and described.

DESCRIPTION

FIG. 1 is a right side elevational view of a clamping pliers with a pistol handle showing our new design;

FIG. 2 is a front elevational view thereof;

FIG. 3 is a left side elevational view thereof;

FIG. 4 is a rear elevational view thereof;

FIG. 5 is a bottom plan view thereof; and,

FIG. 6 is a top plan view thereof.
